JOHN M. WILCOX, OF CLEVELAND, OHIO.

DUMP-CAR.

1,090,001.

Specification of Letters Patent. Patented Mar. 10, 1914.

Application filed October 23, 1912. Serial No. 727,427.

To all whom it may concern:

Be it known that I, JOHN M. WILCOX, a citizen of the United States of America, residing at Cleveland, in the county of Cuyahoga and State of Ohio, have invented certain new and useful Improvements in Dump-Cars; and I hereby declare the following to be a full, clear, and exact description of the invention, such as will enable others skilled in the art to which it pertains to make and use the same.

This invention relates to new and useful improvements in dump cars, and particularly to cars in which the dumping and righting actions are effected by the agency of pressure fluid.

The objects of the invention are the provision of a device of this character which will be of more simple and rugged construction, more efficient in operation, more easily and accurately controlled, more economical in the use of compressed fluid, and less prone to unauthorized operation at the hands of vandals or improper operation at the hands of careless or incompetent workmen than other devices of this character heretofore employed; the provision of an arrangement of dumping apparatus whereby the dumping operation may be accurately and exactly controlled, may be arrested or reversed at any point, and may be effected without the jar and racking of the supporting structure at present observable in most cars; the provision of a mechanism of this character which may be placed entirely under the control of the engineer or of some other authorized person stationed at a single central point, thereby preventing the operation of the same by careless persons or vandals; the provision of a device of this character wherein the operative mechanism may be located at such distance above the track as to be shielded from all danger of injury through derailment or contact with obstructions and without at the same time necessitating the raising of the car body; the provision of new and improved means for locking the car body in horizontal position; the provision of new and improved means for unlocking the car body previous to the dumping action; the provision of means whereby the functions of unlocking and dumping shall be performed by the movement of a single part; the provision of means whereby upon the accidental failure

of the locking mechanism, the dumping of the car can be absolutely prevented by the pressure fluid means, thus avoiding danger to other trains on the road; the provision of a dumping mechanism whereby a single cylinder is employed both for the dumping and the righting of the car body, thus simplifying the construction and lessening the strain upon the car; the provision of a dumping construction wherein the forces tending to incline and right the car are opposed and applied entirely through the mechanism of the dumping apparatus, and not through the structure of the car itself, thereby preventing undue strains upon the car body and the supported structure; while further objects and advantages will become apparent as the description proceeds.

Generally speaking, my invention may be defined as consisting of the features of construction and combination recited in the claims hereto annexed and illustrated in the drawings accompanying and forming a part hereof, wherein:

Figure 1 is an end elevation of a dump car embodying my invention; Fig. 2 is a side view of the central portion of the car; and Fig. 3 is a cross sectional view taken upon the line 3—3 of Fig. 1; Fig. 4 is a transverse cross-sectional view taken on the line 4—4 of Fig. 3 and looking in the direction of the arrows, the car body being shown in inclined position; Fig. 5 is a longitudinal cross sectional view taken through the center of the cylinder and of the operating parts of the car; and Figs. 6 and 7 are detail views of the clutches employed; Fig. 8 is a detail view of a form of valve which may be employed; and Figs. 9 and 10 are detail sectional views of the cylinders 33 and 54 respectively.

The car platform as shown comprises end members 11—11 and a pair of longitudinally arranged sills 12—12 spaced apart upon opposite sides of the car axis and secured to the end members in the usual manner. Tiltably supported above the platform so produced is the car body 13 having trunnions 14 journaled in standards 15 mounted on the car platform so that the said car body can be inclined to either side in the usual manner. The car body is provided with movable sides or doors, shown at 16, which are mounted on the car body by means of arms 17, the said arms being rig-

idly secured to said doors and pivotally secured to the ends of the car body. Between the sills 12-12 is mounted a cylinder 20, here shown as arranged horizontally and 5 extending longitudinally of said platform. In the cylinder 20 is arranged a piston 21 of the usual type having a piston rod 22.

Journalized transversely of the car platform is a rock shaft 23, here shown as supported by standards 24 carried by the sills 12, and mounted on each end of this shaft is a loose sleeve 25 having a radial arm 26. In the present instance these sleeves are held against endwise movement by being 10 extended through the standards 24 as clearly shown in Figs. 1 and 3. The inner end of each sleeve is formed with clutch teeth 27 or similar engaging means, the adjacent ends of these sleeves being spaced 15 apart by a considerable distance as shown in Figs. 1 and 3. Slidably mounted upon the shaft 23 between these sleeves are two 20 slideable clutch-spools 28^a and 28^b, each of which has its outer end formed with teeth 25 or other suitable engaging means adapted 25 to engage with the end of that sleeve toward which it may be shifted. Relative rotation between the spools and shaft is prevented by means of splines or feathers 29. 30 Also the teeth carried by the spools are narrower than the spaces between the teeth 27 of the sleeves, (or if other engaging devices are employed the same are suitably formed so as to permit a small amount of play or 35 lost motion), thus allowing the spools to be moved through a small angle before the arms 26 are actuated. The inner ends of the spools are spaced apart a considerable 40 distance as shown in Figs. 1 and 3, each 45 spool being swiveled to one of the arms 31 of the bifurcated lever 30. The opposite end of this lever is suitably connected to the piston rod 32 of a small cylinder 33 so as to permit the clutch-spools to be shifted 50 along the shaft 23 by the actuation of this piston. Preferably the devices are arranged so that the piston 34 will normally rest at the center of this cylinder, the means here 55 illustrated consisting of balanced springs 35-35 arranged between each end of the cylinder and said piston. Other expedients may obviously be employed to effect this result, or the balancing feature entirely omitted, or in fact, an entirely different operative means may be employed for controlling the clutch-spools. The arrangement herein illustrated is preferred for reasons which will be pointed out hereafter.

To the free end of each arm 26 is secured one end of a link 40, as by means of the universal joint 41, while the other end of said links is secured to the bottom of the car by means of universal joints 42 or in any other convenient manner. At the center of the shaft 23 is rigidly secured a crank

70 arm 43, the distance between the arms 31-31 of the lever 30 being sufficient to permit the same to straddle this crank arm and to allow such movement of the spools 28^a-28^b as will serve to engage and disengage the clutches. The outer end of the arm 43 is operatively connected to the piston rod 22 by any suitable means as by the connecting rod 44.

75 In the present instance the cylinder 20 is shown as rigidly mounted in a horizontal position, but this disclosure is illustrated merely inasmuch as neither horizontality nor rigidity of mounting is essential to my invention, it being merely essential that such connection be had between the piston and the moving part to which it is attached as will effect the movement of the one by the other.

80 In order to prevent the tipping of the car body and premature dumping of its contents, the following arrangement is provided: Pivotally secured to each of the arms 17 is a depending leg 71 formed upon one side with a downwardly facing shoulder 72 and at the opposite side with an upwardly facing shoulder 73. These legs being pivoted at the end of the car, hang down closely adjacent to the end members 11, which end members carry stops adapted to coöperate 85 with the shoulders 72, 73 to limit the movement of those legs. The stop for coöperation with the downwardly facing shoulder 72 is illustrated at 74 and is spaced an appreciable distance below this shoulder during the time that the car body is maintained in horizontal position. The stop which coöperates with the upwardly facing shoulder 73 is shown at 75 (Fig. 3), and is attached to the end of a pivoted strap 76 so as to be displaceable into and out of the path of movement of the leg. This stop engages closely the shoulder of its corresponding leg when the car body is horizontal, thereby preventing the tipping of the same. A 90 spring 77 secured to the strap 76 normally holds the stop 75 in engaging position. This arrangement is preferably duplicated 95 at each end and each side of the car.

100 Journalized to the car platform substantially longitudinally of the car are a pair of rock shafts 78-78, one outside of each of the sills 12-12, and to each end of each of these shafts is attached an arm 79 having articulated to its free end a link 80 the opposite end of which is pivoted to the end of the strap 76. Secured to each of the shafts 78-78 at a point adjacent to the rock shaft 23 is a normally horizontal arm 81 to the outer end of which is secured in any suitable manner, as by the link 84 the pivoted lever 82. Projecting radially from the clutch spools 28^a and 28^b are radial arms 85^a and 85^b respectively, adapted when their respective spools are in engagement with the 110 115 120 125 130

corresponding sleeves to overlap the end of the lever 82 to which they are nearest.

The actuation of the various parts hereinbefore described is effected and controlled by pressure fluid obtained from any suitable source. Under normal conditions the fluid will be compressed air and the same will be obtained from the locomotive, and throughout the remainder of the specification I shall describe the operation of the device by such compressed air, although it will be understood that I do not thereby confine myself to the use of such fluid.

Preferably each car is provided with a storage tank 48 wherein may be contained the fluid necessary to the operation of the car body. While it is, of course, possible from a theoretical point of view that the car might be operated by air pumped directly to the various cylinders from the locomotive, such an arrangement would entirely prevent the operation of the cars if the locomotive should be detached, as is sometimes done before the cars are dumped, and would also greatly delay the dumping of a long train, inasmuch as the locomotive, unless specially equipped, could not deliver air rapidly enough to operate more than a limited number of cars at one time, whereas the provision of a tank with each car permits all of the cars to be operated simultaneously and these tanks replenished at leisure; also the provision of a tank with each car permits the operation of the dumping mechanism with the least possible amount of disarrangement of the air brake system. From this tank a pipe 49 conveys the air to the working cylinder, said pipe having connection with the dumping end of the cylinder by means of the branch 50 and three-way valve 52 and with the righting end of said cylinder by means of the branch 51 and three-way valve 53. Mounted adjacent to the valve 52 is a cylinder 54 having a piston 55 therein provided with the usual piston rod 56 which latter is connected to the handle 57 of the valve 52. A spring 60 coöperating with this piston serves to hold the same near one end of the cylinder 54 and to hold the valve in such position as shall interrupt communication between the branch 50 and the cylinder, while keeping open the communication between the interior of the cylinder and the outside air. Likewise supported adjacent to the valve 53 is a similar cylinder 63 having therein a piston 64 provided with the usual piston rod 65 which latter is attached to the handle 66 of the valve 53. A spring 69 likewise holds this piston toward one end of the cylinder 63 thereby maintaining the valve in a position to prevent communication between the reservoir 48 and the cylinder 20 and to establish communication between the interior of the cylinder and the outside air.

For governing the operation of the mechanism I have illustrated four train pipes 86, 87, 88, and 89 respectively. The train pipe 86 is connected by means of the branch 90 with one end of the cylinder 33, while the train pipe 87 is connected by means of the branch 91 with the opposite end of that cylinder. The train pipe 88 is connected by means of the branch 92 with the cylinder 54, while the train pipe 89 is connected by means of the branch 93 with the cylinder 63. I have not shown any particular means for conveying air to the tank 48 inasmuch as such means is well known in the prior art. Said tanks can be supplied with air either from one or more of the train lines herein illustrated, or by means of a separate train line, or from the brake system, or in any other convenient manner as will be well understood by those skilled in the art.

The operation of the device is as follows: Assuming the car body to be in horizontal position as illustrated in Fig. 1, the piston 1 to be retracted and the clutch spools 28^a and 28^b to be in neutral position as shown in Fig. 3, and the air reservoir 48 to be full of compressed air; the engineer knowing in which direction the cars are to be dumped establishes such variation of pressure in the pipes 86 and 87 as to shift the piston 34 and thereby the clutch spools 28^a and 28^b in such wise as to engage the clutch members upon the opposite side of the car from the side upon which the load is to be dumped. Accordingly, if we assume that it is desired to dump the load upon the left-hand side of the car shown in Figs. 1 and 3, the clutch will be shifted so as to bring the spool 28^b into engagement with the sleeve adjacent thereto and simultaneously to bring the arm 85^b above the end of the adjacent lever 82. It is obvious that at this time the other clutch spool 28^a and the other arm 85^a will be able to swing freely without coming into contact with any obstruction whatever. If now the engineer shall admit pressure to the train line 88 the piston 55 will be actuated to shift the valve 52 and admit pressure fluid from the reservoir 48 to the cylinder 20 displacing the piston 21. The lost motion between the clutch spool 28^b and the teeth of the adjacent sleeve permits the arm 85^b to be swung through a small angle prior to any movement of the arm 26. This movement of the arm 85^b displaces the lever 82 and rocks the shaft 78 thereby withdrawing the stops 75 from the shoulders 73 of the legs 71 of that side of the car which is to be elevated. As soon as these stops have been properly withdrawn the engagement between the teeth of the clutch spool and the sleeve will raise the arm 26 thereby elevating the right hand side of the car body and depressing the left-hand side as shown by the dotted lines in Fig. 1. The depre-

tion of the left hand side of the car carries the legs 71 at that side downwardly until the shoulders 72 thereof come in contact with the stops 74 after which the further movement of the legs is prevented. This then prevents the further movement of the arms 17 and sides 16 without obstructing the movement of the car body, which still continues to move downwardly opening a gap between the sides and bottom for the discharge of the load. Thus far it has been assumed that no pressure has been introduced into the train pipe 89, the valve 53 being left in position to permit the free escape to the atmosphere of the air at the advancing side of the piston. If now it is desired to right the car, the pressure in the train line 88 is reduced, permitting the spring 60 to retract the piston 55 and close communication between the tank 48 and cylinder 20, opening communication between that cylinder and the atmosphere. Now if pressure be admitted to the pipe 89, the tank 48 will be placed in communication with the opposite side of the piston 21 whereby the shaft 23 will be rocked in the opposite direction. The lost motion connection between the clutch spool 28^a and the adjacent sleeve 25 now causes the arm 26 to lag in the opposite direction thus permitting the lever 82 to resume its initial position in advance of the return of the car body to the horizontal. In fact this lost motion may render it impossible for the car body to be brought clear back to its position by means of the piston 21, although the momentum of the body will be sufficient to carry it the last few degrees of its return movement, whereupon the stops 75 will be drawn by the spring 77 into engagement with the shoulders 73 of the legs 71, and the car body securely locked in position. It will be noted that the opposite side of the car body has been unlocked at no time during the dumping operation, wherefore over-throwing of the car body is absolutely guarded against. During this return movement, the air by which the dumping operation was effected has been discharged from the cylinder 20 to the outer air through the discharge port of the valve 52.

In the above description of the operation it was assumed that the valve 53 was set in discharging position during all of the time that the dumping was being effected. In practice this is not the condition, and therein lies one of the important features of my invention. It is obvious from an inspection of Fig. 1 that the inclination of the car body involves a lowering of the center of gravity of the same and its contents which causes the same to fall to the limit of its movement with a very forcible shock unless some means be adopted for restraining the same. Accordingly it is preferred to preface

the dumping operation by opening the valve 53 so as to admit pressure air to the forward side of the piston 21, thereafter admitting air to the opposite side thereof by means of the valve 52. By properly controlling the pressure within the train pipe 89, the operator can then regulate the rate of leakage of air through the valve 53, thereby absolutely controlling the rate of inclination of the car body and preventing any of the hammering and racking of the car body and its supporting structure which has hitherto been so objectionable. In fact, the control is so exact as to permit the partially dumped cars to be restored to horizontal position at will, if need should arise, or to regulate the rate of discharge of contents to the speed most suitable to the handling of the same as is convenient in ballasting a road bed. After the car body has been righted and has been locked by the stops 73, the pressure in the train lines 86-87 may again be equalized, permitting the return of the piston 34 to its initial central position and thereby disengaging the clutch spool 28^a or 28^b. The operation of dumping the cars cannot now be performed by vandals inasmuch as the operation of the piston 21 would serve merely to rotate the shaft 23 without unlocking the car or exerting any strain whatever upon the mechanism. Preferably the mechanism is arranged so as to permit the dumping of the train only from some central point which may be either the engineer's cab or some position along the train. However, for the purpose of permitting the operation of the cars as independent units, I have illustrated cross connections between the various train lines, the same being provided with valves so that air can be transferred from one to the other or to and from the tank 48 thus permitting the operation of each car separately.

While I have necessarily described my invention in detail, it is obvious that a great many changes in point of construction, arrangement, and operation can be effected without departing from the general operative idea or losing to any material degree the advantages of my invention. All of such changes I therefore claim as within the scope of my protection, except as the same may be anticipated in the prior art.

Having thus described my invention what I claim is:

1. In a dump car, the combination, with a supporting structure and a car body pivoted to said structure upon a horizontal axis so as to be tiltable upon either side of said axis, of a fixed cylinder carried by said supporting structure, means for admitting fluid under pressure to said cylinder, a piston in said cylinder, and means whereby a single movement of said piston in one direction may be utilized to cause the inclination of said car body in either direction, and the

- return movement of said piston will right said car body.
2. In a dump car, the combination, with a supporting structure and an elongated car body pivoted thereto upon a substantially horizontal axis and adapted to be inclined in either direction about said axis, the bottom of said car body being spaced above said supporting structure, of a cylinder carried by said supporting structure beneath said car body, a piston in said cylinder, means for admitting pressure fluid to one end of said cylinder to displace the piston therein, means for connecting said piston to said car body intermediate the ends thereof so as to incline the same in either direction by such displacement of said piston, and means for admitting pressure fluid to the opposite end of said cylinder for restoring said car body to its initial position.
3. In a dump car, the combination, with a supporting structure and a car body pivoted thereto upon a fixed horizontal axis so as to be inclined thereabout in either direction, of means comprising a stationary cylinder and a movable piston therein for inclining said car body about its axis, pressure fluid connections to the opposite ends of said cylinder whereby said piston may be operated in different directions, and means secured to said car body intermediate its ends and adapted to be attached in operative relation to said piston whereby a movement of said piston in one given direction may be employed to effect the dumping of the car body to either side.
4. In a dump car, the combination, with a supporting structure, and a flat, elongated car body pivoted to said structure upon a horizontal axis so as to be tiltable upon either side of said axis, of a cylinder carried by said supporting structure beneath said car body, means for admitting fluid under pressure to said cylinder, a piston in said cylinder, means whereby the movement of said piston in one direction may be utilized to cause the inclination of said car body in either direction, and means for retarding the escape of fluid from the other end of the cylinder whereby the inclination of the car body may be cushioned in either direction.
5. In a dump car, the combination, with a supporting structure and a car body pivoted to said structure upon a horizontal axis so as to be tiltable upon either side of said axis, of a single cylinder carried by said supporting structure, a piston in said cylinder, movable devices operatively connected to said piston so as to be movable therewith, tilting devices carried by the car body, and means for connecting said movable devices to either of said tilting devices so as to effect the inclination of said car body in either direction upon the movement of said
- piston in the same direction, the other of said tilting devices being meanwhile disconnected from said movable devices.
6. In a dump car, the combination, with a supporting structure and a car body pivoted to said structure upon a horizontal axis so as to be tiltable upon either side of said axis, of a single cylinder carried by said supporting structure, a piston in said cylinder, movable devices operatively connected to said piston so as to be movable therewith, tilting devices carried by the car body, and means for connecting said movable devices to said tilting devices so as to effect the inclination of said car body in either direction upon the movement of said piston in the same direction, said tilting devices being normally disconnected from said piston.
7. In a dump car, the combination, with a supporting structure and a car body pivoted thereto upon a substantially horizontal axis and adapted to be inclined in either direction about said axis, of a cylinder carried by said supporting structure, a piston in said cylinder, means for admitting pressure fluid to either end of said cylinder to displace the piston therein to the other end, means for connecting said piston to said car body so that the forward movement may incline or tilt the same and its return movement may right or restore the same, locking devices whereby the car body is normally held horizontal, and means operative during the first part of the dumping movement of the piston for disconnecting said locking devices, said locking devices being arranged for reengagement by not later than the conclusion of said righting movement.
8. In a dump car, the combination, with a supporting structure and a car body pivoted thereto upon a substantially horizontal axis and adapted to be inclined in either direction about said axis, of a cylinder carried by said supporting structure, a piston in said cylinder, means for admitting pressure fluid to either end of said cylinder to displace the piston therein toward the opposite end, rigid members secured at opposite sides of said car body, and means for connecting said piston in operative relation to either one of said rigid members, whereby said car body can be inclined in either direction by the operation of said piston in the same direction.
9. In a dump car, the combination, with a supporting structure and a car body pivoted thereto upon a substantially horizontal axis and adapted to be inclined in either direction about said axis, of a cylinder carried by said supporting structure, a piston in said cylinder, means for admitting pressure fluid behind said piston to displace the same, tilting members secured at opposite sides of said car body, and normally disengaged from said piston and means for con-

- necting said piston in operative relation to either one of said tilting members at will, whereby said car body can be inclined in either direction by the operation of said piston in the same direction, said tilting members being inextensible and incompressible whereby said body can be restored to horizontal position by the actuation of said piston in the opposite direction.
10. In a dump car, the combination, with a supporting structure and a car body pivoted thereto upon a substantially horizontal axis and adapted to be inclined in either direction from the horizontal about said axis, of a cylinder carried by said supporting structure, a piston reciprocable within said cylinder, means for admitting pressure fluid to either end of said cylinder whereby said piston may be moved from either end of the cylinder to the other end, mechanism for connecting said piston to said car body so as to oscillate the same in either direction from the horizontal, said mechanism being normally disconnected whereby the unauthorized operation of the dumping means is prevented, and means under the control of the engineer for determining the position of said mechanism.
11. In a dump car, the combination, with a supporting structure and a car body pivoted thereto upon a substantially horizontal axis and adapted to be inclined in either direction from the horizontal about said axis, of a cylinder carried by said supporting structure, a piston reciprocable within said cylinder, means for admitting pressure fluid to either end of said cylinder whereby said piston may be moved from either end of the cylinder to the other end, a movable member operatively connected to said piston and movable to and fro therewith, tilting members secured to said car body at opposite sides of its axis, and means for connecting either of said tilting members to said movable member whereby said car body may be inclined in either direction by the movement of said piston from one end of said cylinder to the other, the other of said tilting members being meanwhile free to follow the movement of the car body.
12. In a dump car, the combination, with a supporting structure and a car body pivoted thereto upon a substantially horizontal axis and adapted to be inclined in either direction from the horizontal about said axis, of a cylinder carried by said supporting structure, a piston reciprocable within said cylinder, means for admitting pressure fluid to either end of said cylinder whereby said piston may be reciprocated, a movable member operatively connected to said piston and movable to and fro therewith, tilting members secured to said car body at opposite sides of its axis, and fluid-pressure-operated devices whereby either of said tilting members may be connected with said movable member whereby said car body may be inclined in either direction by the operation of the piston in the same direction.
13. In a dump car, the combination, with a supporting structure and a car body pivoted thereto upon a substantially horizontal axis and adapted to be inclined in either direction from the horizontal about said axis, of locking means connected to said car body and to said supporting structure whereby the casual inclination of the car body is prevented, a cylinder carried by said supporting structure, a piston movable within said cylinder, means including a lost-motion connection for connecting said piston to said car body whereby the continued forward movement of said piston may incline the same, tripping mechanism for said locking means, and devices movable coincidentally with said piston and adapted to operate said tripping mechanism and release said locking mechanism prior to the inclination of said car body through the medium of said lost-motion connection.
14. In a dump car, the combination, with a supporting structure and a car body pivoted thereto upon a substantially horizontal axis and adapted to be inclined in either direction from the horizontal about said axis, of locking means connected to said car body and to said supporting structure whereby the casual inclination of the car body is prevented, a cylinder carried by said supporting structure, a piston movable within said cylinder, a rigid link articulated to said car body at each side of its axis, means for connecting either of said links to said piston, means for admitting fluid pressure to said cylinder at either side of said piston, tripping mechanism for said locking means, and means whereby the early part of the movement of said piston may operate said tripping mechanism and release said locking mechanism prior to any material inclination of said car body.
15. In a dump car, the combination, with a supporting structure and a car body pivoted thereto upon a substantially horizontal axis and adapted to be inclined in either direction about said axis, of a cylinder carried by said supporting structure, a piston in said cylinder, a substantially horizontal rock shaft journaled in said supporting structure, an arm carried by said rock shaft, connections between said arm and said piston, fluid pressure connections to said cylinder whereby said piston may be displaced and said shaft rocked, oscillable members supported adjacent to said shaft, arms carried by said oscillable members, tilting members secured to said car body and to said arms, and means for connecting said shaft to either of said oscillable members so as to effect the inclination of said car body in

- either direction upon the movement of said rock shaft in the same direction.
16. In a dump car, the combination, with a supporting structure and a car body pivoted thereto upon a substantially horizontal axis and adapted to be inclined in either direction about said axis, of a cylinder carried by said supporting structure, a piston in said cylinder, means for admitting pressure fluid to either end of said cylinder to reciprocate the piston therein, an arm pivoted for movement about an axis substantially transverse to said cylinder, connections between said arm and said piston, oscillable members substantially in alignment with the axis of said arm, tilting members secured to said car body, and to said oscillable members, means including a lost-motion connection for connecting said arm to either of said oscillable members, devices secured to said car body and to said supporting structure whereby said car body is held against casual inclination, tripping mechanism whereby said locking devices may be rendered inoperative, and means movable with said arm and adapted to actuate said tripping mechanism prior to the operation of said tilting devices by the agency of said lost-motion connection.
17. In a dump car, the combination, with a supporting structure and a car body pivoted thereto upon a substantially horizontal axis and adapted to be inclined in either direction about said axis, of a cylinder carried by said supporting structure, a piston in said cylinder, a movable member operatively connected to said piston and movable to and fro therewith, fluid pressure connections to said cylinder whereby said piston and member may be displaced, tilting members secured to said car body, clutch devices for connecting said movable member to one of said tilting members so as to effect the inclination of said car body in either direction upon the movement of said rock shaft in the same direction, and means for normally maintaining said clutch devices in disengaged position.
18. In a dump car, the combination, with a supporting structure and a car body pivoted thereto upon a substantially horizontal axis and adapted to be inclined in either direction about said axis, of a cylinder carried by said supporting structure, a piston in said cylinder, a movable member operatively connected to said piston and movable to and fro therewith, fluid pressure connections to said cylinder whereby said piston and member may be displaced, tilting members secured to said car body, clutch means whereby said tilting members can be connected to said movable member, and fluid-operated mechanism for the operation of said clutch means.
19. In a dump car, the combination, with a supporting structure and a car body pivoted thereto upon a substantially horizontal axis and adapted to be inclined in either direction about said axis, of a cylinder carried by said supporting structure, a piston in said cylinder, a movable member operatively connected to said piston and movable to and fro therewith, fluid pressure connections to said cylinder whereby said piston and member may be displaced, tilting members secured to said car body, an auxiliary cylinder carried by said supporting structure, a piston therein, means operated by said last-mentioned piston for connecting said movable member to said tilting members, and fluid pressure connections to said auxiliary cylinder whereby the operation of said means can be controlled.
20. In a dump car, the combination, with a supporting structure and a car body pivoted thereto upon a substantially horizontal axis and adapted to be inclined in either direction about said axis, of a cylinder carried by said supporting structure, a piston in said cylinder, a movable member operatively connected to said piston and movable to and fro therewith, fluid pressure connections to said cylinder whereby said piston and member may be displaced, tilting members secured to said car body, an auxiliary cylinder carried by said supporting structure, a piston therein, clutch means connected to said auxiliary piston for connecting said movable member to either of said tilting members, said clutch means being disengaged from both members when said auxiliary piston is in the middle of its cylinder and arranged to determine the operation of either of said tilting members depending upon the direction of its displacement, balanced springs normally maintaining said auxiliary piston at the middle of its cylinder, and fluid pressure connections whereby said piston can be displaced in either direction.
21. In a dump car, the combination, with a supporting structure and a car body pivoted thereto upon a substantially horizontal axis and adapted to be inclined in either direction about said axis, of a cylinder carried by said supporting structure, a piston in said cylinder, a substantially horizontal rock shaft journaled in said supporting structure, an arm carried by said rock shaft, connections between said arm and said piston, fluid pressure connections to said cylinder whereby said piston may be displaced and said shaft rocked, tilting members secured to said car body, and means for connecting said tilting members to said shaft, so that said car body will be inclined upon the rocking of the said shaft.
22. In a dump car, the combination, with a supporting structure and a car body pivoted thereto upon a substantially horizontal axis and adapted to be inclined in either direction about said axis, of a cylinder carried by said supporting structure, a piston in said cylinder, a movable member operatively connected to said piston and movable to and fro therewith, fluid pressure connections to said cylinder whereby said piston may be displaced and said shaft rocked, tilting members secured to said car body, and means for connecting said tilting members to said shaft, so that said car body will be inclined upon the rocking of the said shaft.

axis, and adapted to be inclined in either direction about said axis, of a cylinder carried by said supporting structure, a piston in said cylinder, means for admitting pressure fluid to either end of said cylinder to reciprocate said piston, a movable member carried by said supporting structure, connections between said movable member and said piston, whereby the same may be forced 5 to move coincidentally therewith, a tilting member secured to said car body at each side of its pivot axis, means including a lost-motion connection for connecting said movable member to either one of said tilting members, a locking device secured to said car body at each side of its pivot axis, connections between one of said locking devices and the supporting structure arranged to prevent the movement of said car body 10 in one direction, connections between the other of said locking devices and the supporting structure arranged to prevent the movement of said car body in the opposite direction, a tripping device for each of said 15 locking devices, and means movable coincidentally with said piston and adapted to actuate said tripping mechanism and disengage said locking devices, whereby the appropriate locking means is disengaged 20 prior to the inclination of the car body through the agency of said lost-motion connection.

23. In a dump car, the combination, with a supporting structure and a car body pivoted thereto upon a substantially horizontal axis and adapted to be inclined in either direction about said axis, of a cylinder carried by said supporting structure, a piston in said cylinder, means for admitting pressure fluid to either end of said cylinder to reciprocate said piston, a movable member carried by said supporting structure, connections between said movable member and said piston, whereby the same may be forced 25 to move to and fro therewith, a tilting member secured to said car body at each side of its pivot axis, means for connecting said movable member to either one of said tilting members, locking members secured to said car body, devices carried by said supporting structure and engaging said locking members, each of said devices serving to prevent the movement of said car body in one direction from its horizontal position, 30 a tripping device for each of said locking devices, and means movable coincidentally with said piston and in advance of any material movement of said car body and adapted to actuate said tripping mechanism 35 and disengage those locking devices which are associated with the particular tilting mechanism under actuation, the remaining locking devices being unaffected.

24. In a dump car, the combination, with a supporting structure and a car body piv-

oted thereto upon a substantially horizontal axis and adapted to be inclined in either direction about said axis, of a cylinder carried by said supporting structure, a piston in said cylinder, means for admitting pressure fluid to either end of said cylinder to reciprocate said piston, a movable member carried by said supporting structure, connections between said movable member and said piston, whereby the same may be 40 forced to move to and fro therewith, a tilting member secured to said car body at each side of its pivot axis, depending means carried by said car body, stop devices carried by said supporting structure and cooperating with said depending means, there being a stop device for each of said tilting members, whereby said car body is normally held against inclination in the direction in which said tilting member would tend to incline the same, tripping mechanism for each of said stop devices, engaging devices operated by the movement of said piston, and means for connecting said movable member to either one of said tilting members and simultaneously arranging said engaging devices in a manner to permit it to operate the associated tripping mechanism.

25. In a dump car, the combination, with a supporting structure and a car body pivoted thereto upon a substantially horizontal axis and adapted to be inclined in either direction about said axis, of a cylinder carried by said supporting structure beneath said car body and having its axis substantially parallel with the length of the car, a piston in said cylinder, rigid tilting members secured to said car body, means for connecting said tilting members to said piston so that the angle between said car body and said supporting structure may bear a definite relation to the displacement of the said piston from the end of said cylinder, a source of fluid pressure supply, connections between said source and each end* of said cylinder, and a three-way valve in each of said connections arranged to connect said cylinder either with said source of fluid pressure or with the outside air.

26. In a dump car, the combination, with a supporting structure and a car body pivoted thereto upon a substantially horizontal axis and adapted to be inclined in either direction about said axis, of a cylinder carried by said supporting structure, a piston in said cylinder, a source of pressure fluid, means including a three-way valve for admitting pressure fluid from said source to either end of said cylinder to reciprocate the piston therein, tilting members secured to said car body, means for connecting said piston to said tilting members, springs normally maintaining said valves in a position to establish communication between the interior of the cylinder and the open air and

to prevent communication between said cylinder and source, a cylinder adjacent to each of said valves and having a piston therein, connections between each of said pistons and one of said valves, and pressure fluid connections to each of said cylinders whereby the engineer or other central officer can govern the operation of the dumping mechanism.

10 27. In a dump car, the combination, with a supporting structure and a car body pivoted thereon upon a horizontal axis, of a cylinder carried by said supporting structure, means for admitting air to each end of 5 said cylinder, a piston in said cylinder, a shaft operatively connected to said piston so that the movement of the same will rock said shaft, arms loosely mounted on said shaft, clutch members carried by said arms, 15 clutch members on said shaft and adapted to be brought into engagement with the clutch members on said arms alternately, and means operatively connecting said arms with the car body so that the rocking of said 20 shaft will produce a tilting of the car body in the appropriate direction when either of said arms is locked to said shaft.

25 28. In a dump car, the combination, with a supporting structure and a car body pivoted thereto, of a cylinder supported below said car body, means for admitting air to each end of said cylinder, a piston in said cylinder, a piston rod connected to said piston, a shaft extending transversely of said

30 supporting structure, means connecting said piston rod to said shaft so that the movement of said piston rod will rock said shaft, an arm loosely mounted on each end of said shaft, means for connecting either of said arms with said shaft, and link means connecting each arm with the portion of said car body thereabove.

35 29. In a dump car, the combination, with a supporting structure and a car body pivoted thereto upon a longitudinal axis, of a 40 shaft supported transversely of said supporting structure, means for rocking said shaft, an arm pivoted for movement about each end of said shaft, clutch means whereby either of said arms may be secured 45 to said shaft, a clutch shifting lever, an air cylinder operatively connected to said lever so that the movement of the piston of said cylinder in one direction will shift the clutch lever in one direction and the movement of the piston in the opposite direction will shift the clutch lever in the opposite direction, and train lines communicating with the ends of said cylinder whereby the operation of said clutch may be determined by 50 the differences of pressure in said lines.

55 In testimony whereof, I sign the foregoing specification, in the presence of two witnesses.

JOHN M. WILCOX.
